UNITED STATES PATENT OFFICE.

MYRON DINGS, OF MILWAUKEE, WISCONSIN.

ELECTROMAGNETIC SEPARATOR.

SPECIFICATION forming part of Letters Patent No. 755,282, dated March 22, 1904.

Application filed May 23, 1903. Serial No. 158,396. (No model.)

To all whom it may concern:

Be it known that I, MYRON DINGS, a citizen of the United States, residing at Milwaukee, county of Milwaukee, and State of Wisconsin, have invented new and useful Improvements in Electromagnetic Separators, of which the following is a specification.

My invention relates to improvements in magnetic separators.

10 The object of my invention is to provide a form of machine which will occupy a small space, but will be capable of acting upon and effectively separating a maximum quantity of material within a given time.

15 In the following description reference is had to the accompanying drawings, in which—

Figure 1 is a central vertical sectional view of my invention. Fig. 2 is a plan view partially broken away. Fig. 3 is a sectional view drawn on line $\alpha\alpha$ of Fig. 1.

Like parts are identified by the same reference characters throughout the several views.

1 is the core of a stationary electromagnet, of which 2 represents the winding and 3 and 25 4 the respective pole-pieces. The pole-piece 3 is in the form of a vertical semicircular flange connected with the core by a base-flange 5, and the pole - piece 4 is in the form of a horizontal semicircular flange or cap, which projects laterally above the winding 2 at one side of the magnet.

30 6 is a shaft extending vertically through the magnet-core, with its center line preferably located on the opposite side of the center line of the core from that occupied by the pole-pieces 3 and 4. The shaft 6 supports a disk which constitutes a cap-plate 7, to the under side of which rings 8 and 9, of steel or other magnetizable material, are secured by means of screws

40 10. A bracket-ring 11, of non-magnetic material, such as brass, is interposed between the rings 8 and 9, as shown in Fig. 1. The screws 10 are also of non-magnetic material. The rings 8 and 9 are formed in segments α , as clearly shown in Fig. 2, with gaps β between the segments, which are preferably filled with non - magnetic material, such as lead. The lower ring is provided with an annular non-magnetic depending flange 14. The rings 8

50 and 9 and bracket-ring 11 constitute a drum

which is rotated in a horizontal plane through the medium of the shaft and cap-plate 7.

Motion is communicated to the rings from a source of power through a driving-shaft 15, beveled gear-wheels 16 and 17, vertical shaft 55 6, and ring - supporting disk 7, whereby the rings are caused to rotate in a circular path around the magnet, but eccentric thereto.

Above that side of the magnet which is provided with the flanges 3 and 4 is located a semi-conical shield 20, supported from a frame-bar 21 and arranged to distribute material from a slide 22 downwardly past those segments of the rings 8 and 9 which are opposite to and in the magnetic field of the pole-pieces 3 and 4. A counter-shield 25 is used to deflect the material discharged from the semiconical shield 20 into the direct path of the magnetic lines radiating from the ring-segments 8 and 9, the material being, in fact, discharged against 70 the ring - bracket 11 and permitted to pass downwardly by gravity along the faces of this bracket and the segments of the lower ring 9. With this arrangement the magnetite and other magnetically - attracted material discharged from the shield 20 will be collected upon the segments of the rings 8 and 9, while the non-magnetic material, such as sand, will be permitted to pass freely downwardly to a slide 26, which conveys it to a suitable point 80 of final discharge. The magnetite adheres to the ring - segments until carried by the rotation of the rings beyond the magnetic field of the pole - pieces 3 and 4, when, as the segments become demagnetized, this portion of the material is permitted to drop upon the slide 28, by which it is conveyed to a suitable point of discharge on the opposite side of the machine from that occupied by the slide 26. A brush 30, provided with a back 31, is supported, preferably, at an angle of about forty-five degrees from cross-rods 32 in a position to bear upon the exterior surfaces of the rings 8 and 9 on the side of demagnetization, whereby the material adhering to the 95 ring - segments through residual magnetism will be removed. The brush is normally located at one side of the point where the supporting-rod 32 approaches nearest to the rings 8 and 9, thus permitting an adjustment of the 100

brush toward the point of greatest proximity between the rod and rings to take up wear.

It will be observed that by providing a filling of non-magnetic material for the gaps *b* between the ring-segments the magnetite is prevented from becoming lodged in the gaps, and thus magnetically connecting the ring-segments. Also by providing the annular shield 14 the magnetite is prevented from adhering 10 to the under surfaces of the segments of the ring 9 or in the spaces between such segments and the pole-piece 3.

While I have described my invention as involving the use of rings formed in segments 15 with intervening non-magnetic gaps, I do not limit the scope of my invention to a form of construction in which such segments are employed, for it will be understood that, if desired, continuous rings of uniform material 20 may be used. As the magnetic force at the point of contact with the brush 30 will be necessarily weak, owing to the distance between the ring and the pole-pieces at this point, the material may therefore be removed by the brush, even though continuous 25 steel rings are used. While I have also used the term "ring" to describe the segmental carriers for the magnetite, I do not limit the scope of my invention to a form of construction 30 in which such carriers are annular or ring-shaped, as any form of carrier inductively permeable to magnetic lines of force traveling into and out of a magnetic field into which the material is discharged and arranged 35 to permit the free descent of non-magnetized material will come within the scope of my invention.

It will be observed that the pole-piece 4 is inclosed by the connecting drum formed by the 40 rings 8, 9, and 11, while the pole-piece 3 projects into proximity with the lower end of the drum, the magnetic caps between the pole-pieces and the respective rings 8 and 9 being therefore at right angles to each other. The 45 downward magnetic pull of the lower piece tends to draw the top of the shaft toward the left, while the magnetic pull of the upper pole-piece is exerted to draw the top of the shaft toward the right. The magnetic pull of the 50 two pole-pieces is thus balanced and friction on the shaft-bearings due to magnetic side pull is avoided.

Having thus described my invention, what I claim as new, and desire to secure by Letters 55 Patent, is—

1. The combination of a shaft; a pair of rigidly-connected magnetizable rings separated by non-magnetic material, and supported from said shaft; an electromagnet having one pole-piece in proximity to one face of one of the rings, and the other pole-piece in proximity to a face of the other ring substantially at right angles to said face of the first-mentioned ring.

2. The combination of a substantially vertical shaft; a cap-plate therefor of non-mag-

netic material; a pair of magnetizable rings rigidly secured to the under side of the cap-plate; a ring of non-magnetic material interposed between said magnetizable rings; an electromagnet eccentric to the rings and having pole-pieces in proximity to the rings at one side of the magnet; and means for feeding material against the outer faces of the rings. 70

3. The combination of a substantially vertical shaft; a cap-plate therefor of non-magnetic material; a pair of magnetizable rings rigidly secured to the under side of the cap-plate; a ring of non-magnetic material interposed between said magnetizable rings; an electromagnet eccentric to the rings and having pole-pieces in proximity to the rings at one side of the magnet; and means for feeding material against the outer faces of the rings, said magnetizable rings being each formed of a series of segments connected by 80 non-magnetic material. 85

4. The combination of a substantially vertical shaft and a non-magnetic cap-plate therefor; a pair of rings subdivided into insulated segments and connected with the cap-plate; a ring of non-magnetic material interposed between the magnetizable rings, and covering the opposing faces thereof; said non-magnetic ring having a concave outer face; means for feeding material against said concave face; 90 and an electromagnet having pole-pieces in proximity to those portions of the respective magnetizable rings which are traversing the line of feed. 95

5. The combination of a drum formed of magnetizable and non-magnetizable rings revoluble on a vertical axis; an electromagnet eccentrically located within the drum; said electromagnet having one pole-piece projecting at one side of the magnet into proximity 105 with the inner face of the drum near one end and another pole-piece of opposite polarity projecting from the same side of the magnet into proximity with the opposing end of the drum; together with a semiconical distributing-shield secured at its upper end to a frame-bar 21 and having its base covering the side occupied by the magnet pole-pieces, and a concave reversing-shield 25 opposing the lower edge of the distributing-shield. 110

6. The combination of an electromagnet having pole-pieces projecting at right angles to each other and a set of non-magnetically-connected magnetizable carriers arranged to travel into and out of the magnetic field of said electromagnet; one of said carriers being arranged to move over one of said pole-pieces and the other carrier at the side of the opposing pole-piece. 115

In testimony whereof I affix my signature in 120 the presence of two witnesses.

MYRON DINGS.
